UNITED STATES PATENT OFFICE

163,148

GLASS FREEZER JAR

Walter R. Sterrett, Muncie, Ind.

Application September 26, 1947, Serial No. 141,584

Term of patent 7 years

(Cl. D58—25)

To all whom it may concern:

Be it known that I, Walter R. Sterrett, a citizen of the United States and residing at Muncie, in the county of Delaware, State of Indiana, have invented a new, original, and ornamental Design for a Glass Freezer Jar, of which the following is a specification, reference being had to the accompanying drawings, in which

Figure 1 is an elevational view of the jar embodying my new design shown in connection with a dotted-line representation of a closure therefor, which is shown removed therefrom;

Figure 2 is a vertical sectional view along the line II—II of Figure 3; and

Figure 3 is a horizontal sectional view along the line III—III of Figure 1.

The dominant features reside in the portion of the design shown in full lines.

I claim:

The ornamental design for a freezer jar, as shown and described.

WALTER R. STERRETT.
